UNITED STATES PATENT OFFICE.

JOHN R. WYATT, OF PRINCETON, KENTUCKY.

RAILROAD SWITCH.

Application filed November 22, 1924. Serial No. 751,539.

To all whom it may concern:

Be it known that I, JOHN R. WYATT, a citizen of the United States, residing at Princeton, in the county of Caldwell and State 5 of Kentucky, have invented certain new and useful Improvements in Railroad Switches, of which the following is a specification.

This invention relates to improvements in railroad switches and locking means for a 10 rock-shaft having thereon dogs for engagement with switch-point rails, of the type shown by my Letters Patent No. 848,421, dated March 26, 1907; and the invention forming the subject matter of this improvement 15 consists in certain changes in the construction, arrangement, and combination of parts, as will be hereinafter set forth and pointed out in the claims, and the object of my invention is to provide a manually oper- 20 ated lock for holding the rock shaft in non-movable position with the dogs thereon held below plane of the switch-point rails, and when so locked not to interfere with the operation of a throw-bar which is connected 25 with a switch-stand.

The invention also provides a spring actuated rock-bar having thereon dogs which are spring actuated in one direction with means for limiting the rotary movement of the 30 rock-bar.

A further object of my invention is to provide each of the fixed rails of the way with hangers to maintain a rock-bar having thereon dogs for engagement with switch- 35 points, the rock-bar having between one of a pair of hangers a spring for moving the rock-bar in a direction to position the dogs for engagement with the switch-points, the rock-bar having between the hangers at- 40 tached to the opposite fixed rail a stop mem- ber, whereby rotative movement of the rock- bar will be restricted.

A further object of my invention is to pro- 45 vide a construction and means whereby the dogs on the rock-bar will first exert an up- ward pressure against the under side of the switch point rails prior to contact with the flanges of the fixed rails.

A further object of my invention is to pro- 50 vide the rock-bar with flanged collars for engagement with the outer hangers of the fixed rails to hold the rock bar against lat- eral movement in the hangers and to pro- 55 vide for a sliding connection between one of the collars and the rocking-bar of the switch-stand, the other collar serving as a

member of a lock for holding the rock-bar against rotative movement with the dogs below the plane of the switch-rails.

A further object of my invention is to 60 provide switch-rails with beveled flanges so that they may ride upon the flanges of the fixed rails and when so positioned the points will be on the same plane as the head of the 65 fixed rail.

Means for attaining the several objects of my invention are illustrated in the accompanying drawings, in connection with a switch-stand as shown in my prior patent heretofore mentioned, and in said draw- 70 ings—

Fig. 1, is a plan view of the switch oper- ating and locking mechanism.

Fig. 2, is a transverse section on the line 2—2, Fig. 1.

Fig. 3, is a detail section taken vertically on the line 3—3, Fig. 1.

Fig. 4, is a detail section taken vertically on the line 4—4, of Fig. 1.

Fig. 5, is a side elevation and section, the 80 section being taken on the line 5—5 of Fig. 4.

Fig. 6, is a plan view of the end portion of one of the switch-point rails.

Fig. 7, is a plan view of the other switch- 85 point rail; and

Fig. 8, is a side elevation partly in section of the switch-stand, which is preferably used to operate the rock-bar and throw the switch-points or rails.

The switch-stand shown by Figures 1 and 90 8 of the drawings is substantially the same as illustrated in my previously mentioned patent, and when it is desired to move the switch-points or rails from the position shown by Figure 1 of the drawings, which 95 show the main track open for traffic. When it is desired to move the switch-points the hand-lever 9 that is pivoted to a horizontally movable head of the switch-stand is swung upward so that its upper end will engage and depress a vertical rod 10, said rod engaging a crank 11 on a rock-shaft 12. The rod 10 is encircled by a spring 13 the tendency of the spring being to hold the crank 11 raised, 100 and rail engaging dogs or lugs in engage- ment with the movable switch-points, and when the rod is depressed to position the dogs or lugs below the plane of the switch- points or movable rails. The lever 9 having been raised to a horizontal position is moved 110 to turn the now unlocked head of the switch- stand a quarter turn the head carrying with

it the signal and throw-bar rod 14 by which the switch-points are moved.

The rock-shaft 12 carries collars which are located on opposite sides of an apertured hanger through which said shaft is passed and has a limited play in the hanger. The end of rock-shaft is key shaped or rectangular to enter a square socket 15, formed in a collar 16 having a flange 17, the collar being 10 fastened securely to the end of a rock-shaft 20.

The throw-bar 18 is connected to the crank end of the vertical rod 14, being held in engagement therewith by a cotter or other 15 pin, the opposite end of the throw-bar 18 is held in pivotal engagement with a bar 19 that is attached to the switch-point rails, preferably by means of a bolt and nut. The means for connecting the throw bar 18 with 20 the bar 19, and the rock-shaft 12 with the rock-shaft 20, is preferred as it admits of ready separation of the parts in setting up and taking down or away the switch stand, and further the construction admits of the 25 use of a lock for holding the rock-shafts inoperative when desired with the dogs on one of said rock-shafts in position below the plane of the base of the rails of the way, without interfering with the operation of 30 the lever of the switch-stand or the movement of the switch points.

The locking means in simple form consist in providing the rock-shaft 20 on its end opposite to the collar 16 with a flanged collar 21 the same having therethrough an aperture which is adapted to be brought in register with an aperture through a hanger 22 secured to one of the outer rails. When the apertures are in register a pin 23 is 35 passed through the apertures and the rock-shaft 20 will be held against rotation with the switch point engaging lugs 24 below the plane of the base of the rails, and in an inoperative position. A spring 25 which encircles the rock-shaft between the hangers 40 26 attached to the fixed rail that is nearest to the switch-stand, the tendency of this spring 25, being to turn the rock-shaft 20 to elevate the dogs or lugs 24 that are attached 45 thereto. When the lock is in use it will not in any way interfere with the throwing or operation of the switch rails by the lever 9, which moves the turning head of the 50 switch stand, the vertical rod 14 and throw-bars 18 and 19, the latter being attached to the 55 switch points or movable track points.

The two fixed rails 27 and 28 of the way have bolted or otherwise secured thereto, between the switch supporting ties for the 60 switch stand, similar hangers 22 and 30 which maintain the rock-shaft 20, that is of sufficient length to extend beyond the outer hangers for attachment thereto of the fixtures or collars, and between the hangers 65 22, the rock shaft 20 has rigidly attached

thereto a sleeve 31 that has a projection 32 for engagement with the underside of the base of the rail 27 to limit the rotation of the rock-shaft 20 and prevent movement of the lugs or dogs 24 beyond a vertical position 70 or set by the action of the springs 13 and 25, to hold the movable rails in locked position, as shown by Figs. 1 and 3 of the drawings.

The flange of the base portion of the 75 switch-point rail 34 is cutaway or recessed as shown at 35, to provide a clearance for the inner hanger attached to the rail 28, also to provide a flat surface against which the side edge of the dog may abut when elevated. The switch point 33 is also cut away to form a clearance for the inner hanger of the fixed rail 27, and the undersides of the switch point rails are beveled as shown, the 80 bevels 36, formed by cutting away the under faces of the switch point rails, permit the rails to ride upon the inner flanges of the fixed rails so the treads of the rails will be 85 on the same horizontal when in contact.

It will be noted that by my invention I 90 provide a double lock for the main rails of the way, one of the locking or holding means being the throw bar 14 which is moved by the lever 9 to position its bent end in line with bar 18 that is pivoted to the bar 19 that is secured to the switch points, the second lock being the rock-shaft 20, which carries the dogs or lugs 24 that are moved upward to engage and lock the switch points, and are further held in a raised position by the 95 spring 13, on the switch-stand and by a spring 25 that is attached to the rock shaft 20, the spring 25 being partially housed between the hangers 30. It will also be noted that a collar 31 on the rock-shaft 20, which 100 collar has a projection 32 which serves to limit the movement of the rock-shaft 20, when the dogs 24 are in raised position, and that an auxiliary lock comprising a collar 105 having a flange with an aperture therethrough for the passage of a pin or bolt, or other means that engages with a fixed hanger may be used to lock the rock bar having thereon the dogs, with said dogs held out of 110 operative position, so as to admit of the switch being thrown to either position with the rock-shaft and the dogs being held in 115 non-operative position.

I claim.

1. In switch mechanism, the combination 120 with a rock-shaft having dogs for engagement with switch-points of railroad rails, hangers attached to fixed rails to carry the rock-shaft, a member fixedly attached to the rock-shaft, and means for engagement therewith and with one of the hangers to hold the rock-shaft against movement and the dogs thereon in inoperative position.

2. The combination in switch operating 125 mechanism of a rock-shaft, switch point en- 130

- gaging dogs attached to the rock-shaft, hangers attached to and depending from non-movable rails for carrying the rock shaft, a member fixedly attached to an end 5 portion of the rock-shaft and means for holding said member in non-rotative engagement with one of the hangers.
3. The combination in switch operating mechanism of a rock shaft, switch-point en- 10 gaging dogs attached to the rock-shaft, hangers attached to fixed rails for maintaining the rock-shaft, one of said hangers having an aperture therethrough, a disk at- tached to the rock-shaft and provided with 15 an aperture which is adapted to aline with the aperture through said hanger, and means insertable through the apertures when in alinement to hold the dogs on the rock-shaft below the plane of the switch-points.
- 20 4. In railway switch operating mechanism, the combination with a rock-shaft having fast thereon switch-point engaging dogs, a spring on the rock-shaft for moving the same to position the dogs in position to en- gage and lock the switch-points, and means carried by the rock-shaft to restrict the turning movement of the rock-shaft.
- 25 5. In railway switch operating mechanism, a rock-shaft provided with switch- point engaging dogs, a spring mounted on 30 the rock-shaft said spring exerting a tend- ency to turn the rock-shaft to position the dogs in engagement with switch-points, means for restricting the rotative movement of the rock-shaft, and means for locking the 35 rock-shaft to hold the dogs in inoperative position.
6. In combination with a switch-stand, a manuallly movable and spring actuated rock- 40 bar, a rock-shaft having switch-point engag- ing dogs thereon, a spring on the rock-shaft; both of said springs co-acting to turn the rock-shaft having the dogs thereon to switch- point engaging position and means for lim- 45 iting the rotative movement of the rock- shaft.
7. In switch operating mechanism the combination with a switch-stand having a throw-bar connected with switch-points, and a member for moving a rock-shaft prior to 50 the actuation of the throw-bar, dogs on the rock-shaft which are moved and held below the plane of the switch points until the full throw of the throw bar, and springs on the rock-shaft having thereon the dogs and on 55 the switch-stand member for moving the rock-shaft.

JOHN R. WYATT.
